UNITED STATES PATENT OFFICE

DONALD G. SMELLIE, OF CANTON, OHIO, ASSIGNOR TO THE HOOVER COMPANY, A CORPORATION OF OHIO

SUCTION CLEANER AGITATOR

Application filed November 6, 1929. Serial No. 405,092.

The present invention relates to suction cleaners and more particularly to suction cleaner agitators of the rotary type. The invention has for its object the provision of an agitator for a suction cleaner which is of simple construction and which may be economically manufactured; the provision of an agitator constructed in a new and novel manner. Other and more specific objects will appear from a consideration of the following specification and the drawing annexed thereto.

Referring now to the drawing:

Figure 1 is a side view of an agitator constructed in accordance with the present invention;

Figure 2 is a cross section upon the line 2—2 of Figure 1;

Figure 3 is a cross section upon the line 3—3 of Figure 1;

Figure 4 is a cross section upon the line 4—4 of Figure 1;

Figure 5 is a modified embodiment of the present invention;

Figure 6 is a cross section upon the line 6—6 of Figure 5;

Figure 7 is a view in perspective of a further modification of the present invention.

Referring now to Figures 1 to 4 in particular, a preferred embodiment of the present invention is disclosed and comprises an agitator having end plates 1 and 2 carried at the ends of the web 3. End plates 1 and 2 are secured in any suitable manner as by welding.

Web 3, as disclosed in Figures 2, 3 and 4, is an elongated plate of relatively narrow width at its center 4, but with thickened and rounded edges forming beater bars 5, 5. The member is warped in the sense of being twisted or folded, throughout its length so that the edges

5, 5 describe helices of opposite angularity extending substantially through an angle of 180° circumferentially. In order that the agitator may be driven by the motor of the suction cleaner the end plate 2 is made greater in width than end plate 1 and is provided with a grooved portion 6 forming a pulley which is adapted to receive a driving belt connected to the pulley of the driving motor shaft. The pulley 6 is of sufficient depth so that when the belt is in position thereon it will not pro-

trude beyond the circumference of the plate 2. Stub-shafts 7 and 8 are provided upon the end plates 1 and 2 respectively, which are adapted to be positioned within suitable bearing mountings in order that the agitator may be rotatably supported within the nozzle of a suction cleaner. The particular manner in which the agitator is supported in the nozzle forms no part of the present invention.

Referring now to Figures 5 and 6 in particular, a modified embodiment of the present invention is disclosed in which the smooth contour of the warped plate 3 is interrupted between its ends by the presence of a section of reduced width which is adapted to receive a pulley indicated by the reference character 9. Pulley 9 comprises two half-sections 10 and 11 having inner faces 12 and 13 which conform to the sides of the plate 3. The outer surfaces of the half-sections 10 and 11 are semi-circular and form, when positioned upon the agitator with the projecting portions, 14, 14 and 15, 15 overlying the edges of the reduced section of the web 3, a circular pulley. Securing screws 15, 16 are provided which pass from section 10, where their heads are positioned below the surface of the pulley in recesses 17, 17, through the web 3 and into threaded seats 18, 18 in the half-section 11. In this embodiment as the agitator is driven by a pulley positioned at the center thereof the end plates 1 and 2 may be made identical and the recessed portion 6 of end plate 2, shown in the preferred embodiment, is unnecessary. The present embodiment has the advantage that it may be used in suction cleaners in which the driving belt is positioned in the center of the cleaner.

Referring now to Figure 7 a modification of the present invention is disclosed in which an agitator constructed as shown in Figures 1 to 4 inclusive, is provided with a cylindrical body 19 between the end plates 1 and 2 respectively. Body 19 is preferably molded upon the agitator after its complete assembly and may be made of bakelite or any suitable moldable material. The diameter of the cylindrical body is substantially equal to the diameter of end plates 1 and 2, so that in

the completed form only the rounded beating edges 5, 5 of the web 3 are visible between the plates 1 and 2, the remainder of the web being embedded in the body. The present embodiment requires only the additional step 5 of molding upon the agitator disclosed in Figure 1, the cylindrical body 19 and has the desirable characteristic of functioning with less fan action in the suction nozzle when in use.

10 In the operation of an agitator constructed in accordance with the present invention the agitator is mounted within the suction nozzle of a suction cleaner upon some suitable bearing support with the stub-shafts positioned therein.

15 The driving belt of the suction cleaner is connected to the pulley of the agitator and the agitator is revolved at high speed. The suction in the cleaner nozzle lifts the surface covering undergoing cleaning 20 into contact with the revolving agitator and the rounded edges 5, 5 function as beater bars to dislodge the embedded foreign matter by impaction.

25 The cleaning action of the present agitator is that characteristic of the usual positive agitator and no invention is claimed therein but what is claimed as the applicant's invention is an improved and simplified agitator construction which is characterized by 30 simplicity, durability and efficiency as set forth in the following claims.

I claim:

1. A suction cleaner agitator comprising 35 spaced end members, means to rotatably support said end members and means maintaining said end members in fixed relative relation comprising a plate rigidly attached thereto the edges of which form beater elements.

40 2. A suction cleaner agitator comprising spaced end plates, means to rotatably support said end plates and means maintaining said end plates in fixed relative relation comprising a folded web rigidly attached to said end plates, the edges of said web being at equal radial distances from the common axis of the end plates said edges extending in curves and forming beater elements.

45 3. An agitator for suction cleaners comprising a plate folded in opposite directions at its opposite ends, the edges of the plate between their ends forming oppositely advancing helices at a constant radial distance 50 from the major axis of the plate, the said edges being rounded and forming beater elements, supporting means at the ends of said plate, and means connected to said plate to receive a rotating force.

55 4. An agitator for suction cleaners comprising a web having rounded edges, a cylindrical body partially encasing said web with the rounded edges extending therefrom and means to rotatably support said agitator.

60 5. An agitator for suction cleaners com-

70 prising a warped web having rounded edges forming beater elements, a cylindrical body partially encasing said web with the rounded edges extending therefrom, means to rotatably support said agitator and means secured to the web whereby the web may be rotated.

75 6. An agitator for suction cleaners comprising a web having rounded edges, said web being folded so that said rounded edges describe helices having opposite angularity, a cylindrical body partially encasing said web with the rounded edges extending therefrom, means to rotatably support said body, and means secured to the web whereby it may be rotated.

80 7. An agitator for suction cleaners comprising a web having spaced rounded edges, an elongated body partially encasing said web with the rounded edges extending therefrom, and means to rotatably support said 85 agitator.

85 8. An agitator for suction cleaners comprising a plate folded in opposite directions at its opposite ends with its edges therebetween forming oppositely advancing helices at a constant radius from the major axis of the plate, the edges of said plate forming beater elements, supporting means at the ends of said plate and means at substantially the center thereof and connected thereto to receive a rotating force.

90 9. A suction cleaner agitator comprising a warped plate the edges of which extend at a constant distance from and describe helices about the major axis of the agitator and form beater elements, and means to rotatably support said plate.

95 Signed at Canton, in the county of Stark, and State of Ohio, this 1st day of November, A. D., 1929.

DONALD G. SMELLIE.
